(57) **CLAIM**

The ornamental design for a telecommunications box, as shown and described.

DESCRIPTION

FIG. 1 is a top perspective view of a telecommunications box showing our new design;

FIG. 2 is a bottom perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines shown throughout the views, which are immediately adjacent to the claimed surfaces, represent the bounds of the claimed design, while all other broken lines are directed to environment and are for illustrative purposes only; the broken lines form no part of the claimed design.
